STIRRUP FOR JACK STICKS IN LOOMS

Clarence E. Kennett, Warrenville, S. C.

Application September 20, 1947, Serial No. 775,218

3 Claims. (Cl. 139—88)

1

This invention relates to an improved stirrup for jack sticks in looms. In the treadle type of loom, there are plurality of levers which are cam operated and which have connected thereto suitable jack sticks which in turn are connected to the lower sides of harness frames with suitable means for suspending harness frames, sometimes tension take-up means, whereby the jack straps are moved upwardly and downwardly by the treadles to form sheds in a weaving operation and the harnesses along with the treadles and jack sticks are returned to raised position by conventional means such as tension elevating means.

In conventional jack sticks, they have usually been made similar to the structure shown in the patent to Emmons, No. 1,944,971, of June 30, 1934, in which a stirrup has been provided at a proper location, not necessarily in the middle of the jack stick so as to cause this stirrup to coincide with the particular treadle in a loom. Since looms have two to six and sometimes more treadles, it is therefore necessary to have a different type of jack stick on hand for replacement for each treadle in the loom. Since these stirrups are very narrow only a particular jack stick having a stirrup located at a particular point will do for a particular treadle.

It is an object of this invention to provide a jack stick having a stirrup, the side portions of which are far enough apart to cover the range of the width of the treadles and with the lower ends of the stirrup having a rod extending thereacross with a collar adjustably mounted on the rod so that one jack stick can serve for use in connection with any one of the different treadles in a loom merely by adjusting the collar thereon at the proper position to correspond to the particular treadle and its jack strap with which it is to work.

It is another object of this invention to provide a jack stick for looms having a stirrup much broader than the conventional stirrup with a collar adjustably mounted for lateral movement therealong and adapted to be adjusted in a fixed position to receive a jack strap from a particular treadle in a loom.

Some of the objects of the invention having been stated, other objects will appear as the description proceeds when taken in connection with the accompanying drawings, in which

Figure 1 is a vertical sectional view, mostly in elevation and showing a pair of the treadles of a loom and a pair of the jack sticks and jack straps associated therewith;

2

Figure 2 is an elevation looking from along the line 2—2 in Figure 1;

Figure 3 is a vertical sectional view taken along the line 3—3 in Figure 2;

Figure 4 is a longitudinal sectional view taken along the line 4—4 in Figure 3, and at the central portion of the stirrup.

Referring more specifically to the drawings, the numeral 10 indicates a jack stick, two of which 10 are shown in the drawings. These jack sticks have suitable eye bolts 11 disposed at each end thereof, in each of which there is pivotally mounted for practically universal movement, a jack hook 12 which is adapted to hook in a suitable eye bolt 15 secured in the lower edge of the harness frame. These jack sticks heretofore have had a suitable stirrup member located somewhere near the middle portion of the jack stick for engagement with suitable jack strap or connecting rod.

As before pointed out in this type of jack stick, it is necessary to have a big supply of jack sticks with the stirrups located at different positions to correspond to the various treadles of the loom. The loom has a plurality of treadles 14, two of which 14 are shown and these are pivoted as at 15 and are depressed by means of suitable cams 16 mounted on a cam shaft 17. These treadles 14 have a plurality of notches 18 in their lower edges in which suitable links 20 are disposed and to the upper end of these links are secured suitable jack straps 21. These jack straps have heretofore been secured to the conventional treadles in the jack stick.

In the present invention instead of having a conventional stirrup, I provide a pair of rods 25 and 26 which penetrate the jack sticks 10 in spaced relation to each other and are bradded as at 27. The lower ends of these rods 25 and 26 are bent into a circular formation and are penetrated by an elongated bolt 28 which has nuts 29 and 30 adjacent each end thereof on opposite sides of the rods 25 and 26 to securely hold the bolt 28 in position in the lower ends of the rods 25 and 26.

Slidably mounted on the bolt 28 is a collar member 35 which is adapted to be fixed in adjusted position by means of a set screw 36. This collar 35 has flanged portions 37 and 38 at its ends and can be slightly crowned, that is slightly of greater diameter near its center if desired, though a preferably cylindrical collar 35 would operate satisfactorily.

By this arrangement, the collars 35 can be adjusted to any desired position to receive the jack straps 21 and thus one type of jack stick

can be used for anyone of the plurality of harnesses and treadles associated therewith in a loom.

In the drawings and specification there has been set forth a preferred embodiment of the invention, and although specific terms are employed, they are used in a generic and descriptive sense only and not for purposes of limitation, the scope of the invention being defined in the claims.

I claim:

1. In a loom having a plurality of treadles and a plurality of jack sticks and jack straps connecting the treadles to the jack sticks, each jack stick having secured thereto and projecting downwardly therefrom a pair of spaced members, a horizontally disposed member spanning the distance between and secured to the lower ends of the downwardly projecting spaced members and a collar member slidably mounted for movement along the horizontally disposed member and on which a jack strap is adapted to be mounted, and means for adjustably securing the collar member in position on the horizontally extending member.

2. A jack stick for looms having a pair of downwardly projecting spaced members secured thereto and intermediate the ends thereof, the lower ends of said downwardly projecting spaced

members being joined together by a horizontally disposed member, and a collar member mounted for movement along said horizontally disposed portion for receiving a jack strap of the loom.

5 3. In a jack stick for looms, said looms having a plurality of treadles and a plurality of jack straps for connecting the treadles to the jack sticks, said jack sticks having a pair of downwardly projecting parallel members and a horizontally extending member joining the lower ends of the downwardly projecting parallel members, a cap member slidably mounted on the horizontally extending member and having means for adjustably securing the same in any desired 10 position along the horizontally extending member to receive a jack strap at any desired position along the length of the horizontally extending member.

CLARENCE E. KENNEDY.
